(57) **CLAIM**

The ornamental design for a wrist pad for lap desks, as shown and described.

DESCRIPTION

FIG. 1 is a front, left, elevated, quartering perspective view of a new design for a wrist pad for lap desks;

FIG. 2 is a section view, as indicated in FIG. 3, of the new design of FIG. 1 showing the interior shape of a device slot in the top surface thereof.

FIG. 3 is a top plan view of the new design of FIG. 1; FIG. 4 is a front elevational view of the new design of FIG. 1;

FIG. 5 is a rear elevational view of the new design of FIG. 1;

FIG. 6 is a right-side elevational view of the new design of FIG. 1; and,

FIG. 7 is a left-side elevational view of the new design of FIG. 1.

The dashed lines included within the figures represent environmental structure only and do not form part of the claimed design.
